UNITED STATES PATENT OFFICE.

ISAAC P. WOODARD, OF RICHMOND, INDIANA.

COMBINED FODDER-CUTTER, CORN-SHELLER, AND FEED-MILL.

SPECIFICATION forming part of Letters Patent No. 294,423, dated March 4, 1884.

Application filed November 23, 1883. (No model.)

To all whom it may concern:

Be it known that I, ISAAC P. WOODARD, a citizen of the United States, residing at Richmond, in the county of Wayne and State of Indiana, have invented certain new and useful Improvements in Combined Fodder-Cutter, Corn-Shellers, and Feed-Mill, of which the following is a specification, reference being had therein to the accompanying drawings.

10 My invention relates to that class of fodder-cutters, corn-shellers, and feed-mills used by farmers on their farms.

My invention consists in the combination of a fodder-cutter, corn-sheller, and feed-mill in a single frame, in a manner to be hereinafter described, whereby economy and compactness of construction are attained and the machines made capable of separate or simultaneous use.

In the drawings, Figure 1 is a side elevation 20 of the apparatus, showing the box of the fodder-cutter attached. Fig. 2 is a side elevation of the apparatus with the side of the casing removed. Fig. 3 is a top or plan view, showing the arrangements of the operating devices 25 and their connection. Fig. 4 is a view of the wheel of the fodder-cutter.

$\alpha\alpha\alpha$ represent the framing which incloses and supports the operative devices used.

a represents a pulley upon the outer end of 30 a shaft, b , which extends across the frame in a central position, as seen in Fig. 3, and is provided with suitable boxings or bearings.

c is a feed-mill of any suitable construction, the stationary parts of which are attached to 35 the framing α , the rotary parts being operated by the shaft b .

At the opposite end of the shaft b from the pulley a , and outside the framing, is fixed a bevel-pinion, d , which engages a corresponding wheel, e , which operates the feed-roller s of 40 the fodder-cutter.

g is a belt passing over and actuating a pulley, t' , on a shaft, t^2 , (see Fig. 1,) which carries an elevator, h , which delivers the shelled 45 corn into the spout l , from which it passes into the hopper m of the feed-mill e ; or the corn may be diverted into the spout J , (see Figs. 1 and 2,) and taken from the machine without grinding.

50 h is a spout or conductor, by which the meal

from the feed-mill is carried into a proper receptacle.

u is an elevator-box inclosing the elevator h . p is a pulley fixed upon the outer portion of the shaft b' . The shaft b' has its bearings 55 on the cross-framing $\alpha\alpha$, having upon it the driving cog-wheel o and the corn-sheller wheels $s s$. The pinion r is fixed upon the shaft b , and through the intervening pinion r' engages with the cog-wheel o and gives motion to the corn-sheller wheels $s s$. The sheller-wheel t , rigidly fixed upon the shaft b , is placed so as to revolve centrally between the inner surfaces of the sheller-wheels $s s$.

i is an endless-chain cob-carrier, constructed 65 in such manner as to allow the shelled corn to fall through it into the reservoir z , Fig. 2, whence it is carried up to the mill-hopper m or spout J for delivery, while the cobs are carried forward on the endless chain and discharged at the side of the machine.

u , Figs. 3 and 4, is a wheel placed upon the shaft b just within the cross-framing α , and rigidly secured to the shaft b , turning with it. This wheel performs the part of a balance-wheel in reference to the feed-mill and corn-sheller, and at the same time carries the knives $v v$ of the fodder-cutter, as seen in Fig. 4. Arms 1 2 3 4 extend beyond the rim of the wheel u , projecting sufficiently to act as clearing-arms 80 in removing the fodder as it is cut and dropped from the cutter when the wheel is in motion. The feed-roller s of the fodder-cutter in hopper f is revolved by suitable devices, which connect it with the power-shaft, the means 85 shown in the drawings consisting of a bevel-pinion, d , wheel e , shaft e' , and gear-wheels e^2 , e^3 , and e^4 . (See Figs. 1 and 3.) I do not regard this method, however, as essential to the 90 operation of my invention.

I do not confine myself to the use of any particular construction of fodder-cutter, corn-sheller, or feed-mill. It will be seen that each one of the machines thus combined is operated directly by and through the shaft b , and that 95 the wheel u does service as a balance-wheel in equalizing the motion of either one or of all the different machines, and that one or more of them can be used at the same time.

w is a hinged door in front of the cut-fodder 100

apartment, and may be raised or depressed on its hinges, as required.

Having thus fully described my said invention, what I claim as new, and desire to secure 5 by Letters Patent, is—

The herein-described apparatus, comprising the supporting-frame, the main power-shaft, a rotary fodder-cutter, a corn-shelling wheel, *t*, a feed-mill having its rotary parts mounted 10 upon said shaft, fodder-feeding devices, a counter-shaft mounted parallel to said main shaft, and carrying rotary devices constructed

to co-operate with said wheel *t* as a corn-sheller, suitable power-transmitting devices connecting said shafts, and an elevator and 15 spouts arranged to deliver the shelled corn from the sheller to the feed-mill, substantially as set forth.

In testimony whereof I affix my signature in presence of two witnesses.

ISAAC P. WOODARD.

Witnesses:

JOHN F. ROBBINS,
W. T. DENNIS.
